TOOTH STAIN-REMOVER TIP FOR
TOOTHBRUSHES AND THE LIKE

Lewis James Halberstadt, Williamsburg, Mass., assignor
to Vistron Corporation, Cleveland, Ohio

Filed Sept. 3, 1971, Ser. No. 177,914

Term of patent 14 years

Int. Cl. D4—02

U.S. Cl. D4—24

FIG. 1 is a perspective top view of a tooth stain-remover tip showing my new design;

FIG. 2 is a top plan view thereof;

FIG. 3 is a side elevational view;

FIG. 4 is a bottom plan view;

FIG. 5 is an elevational view taken from one end in the direction of line 5—5 of FIG. 2;

FIG. 6 is an elevational view taken from the end opposite that in FIG. 5 in the direction of line 6—6 of FIG. 2; and

FIG. 7 is a side sectional view taken along the line 7—7 in FIG. 2.

The broken line representation of a toothbrush is for purposes of illustration only.

I claim:

The ornamental design for a tooth stain-remover tip for toothbrushes and the like, as shown and described.
